CLAIM

The ornamental design for a roof tile having simulated wood appearance, as shown and described.

DESCRIPTION

FIG. 1 is a perspective view of my new roof tile design; FIG. 2 is a top plan view thereof;

FIG. 3 is a bottom plan view thereof, illustrating functional ribs used in the underside of the tile not being part of the claimed invention;

FIG. 4 is a front elevational view thereof;

FIG. 5 is a rear elevational view thereof;

FIG. 6 is a right side view thereof; and

FIG. 7 is a left side view thereof; and,

FIG. 8 is a second embodiment of the claimed invention. The bottom, rear, and opposite side of the roof tile in FIG. 8 are substantially the same as those views of the roof tile in FIGS. 3, 5, and 7.

The broken lines disclosing ribs are for illustrative purposes and form no part of the claimed design.
